UNITED STATES PATENT OFFICE.

HOMER J. ROBERTS, OF EVANSTON, ILLINOIS.

ELECTRICAL-IMPULSE-COUNTING SWITCH.

No. 851,081.

Specification of Letters Patent.

Patented April 23, 1907.

Application filed November 4, 1905. Serial No. 285,829.

To all whom it may concern:

Be it known that I, HOMER J. ROBERTS, a citizen of the United States, residing at Evanston, in the county of Cook and State of Illinois, have invented certain new and useful Improvements in Electrical - Impulse-Counting Switches, of which the following is a specification.

This invention relates to electrical - impulse-counting switches adapted for use in connection with selective party - line telephone systems and analogous purposes.

Among the salient objects of the present invention are to provide a switch mechanism whereby any given number of impulses within the range of the capacity of the instrument may be thrown upon a circuit connected with the switch and the sending of further impulses automatically interrupted at the end of the predetermined series; to provide in a switch of the character referred to means for utilizing pulsating current derived from a suitable source, the switch mechanism being so organized as to prevent the sending to line of fragmentary parts of impulses which would destroy or tend to destroy reliability of selection; to provide in a switch of the general character referred to means for utilizing unidirectional pulsating current and automatically reversing the connections with the source of current at a predetermined time in such manner as to send to line a definite number of impulses of one polarity and succeeding impulses of different polarity; to provide in such a switch mechanism electrical controlling mechanism which governs the movement of rotation of the switch and insures a mechanical stepping forward of the switch in synchronism with the electrical pulsations passing therethrough; to provide in such a switch means whereby current impulses of alternately-opposite polarity may be utilized, the impulses of one polarity being sent direct to line without passing through the controlling-magnet of the instrument and the impulses of opposite polarity being passed through the magnet of the instrument and serving to actuate the instrument; to provide in such an instrument improved means for quickly and accurately setting the switch to count out the desired number of impulses; to provide in conjunction with such a switch and a suitable source of pulsating current an improved system of circuit connections and accessories whereby the switch may be conveniently

connected with any one of a plurality of subscribers' telephone - lines; to provide improvements of the details in construction and arrangement contributing to the efficiency, accuracy, and reliability of the instrument, and, in general, to provide an improved system of the character referred to.

To the above ends the invention consists in the matters hereinafter described, and more particularly pointed out in the appended claims.

In the drawings, Figure 1 is a plan view of a switch mechanism embodying the invention, the front broad of the switchboard with which the switch is connected being shown in horizontal section as well also as the dial of the instrument. Fig. 2 is a rear end face view of the instrument, certain parts being broken out to show the recesses engaged by the wipers of the switch-springs. Fig. 3 is a front end face view or elevation of the instrument, a fragment of the dial being broken out to show one feature of adjustment. Fig. 4 is a transverse vertical sectional view taken on line 4-4 of Fig. 1 and looking in the direction of the arrows. Fig. 5 is a view similar to Fig. 4, taken on line 5-5 of Fig. 1 and looking in the direction of the arrows. Figs. 6 and 7 are sectional details of the set of contact-springs and the hub of the instrument which they engage, Fig. 6 being an enlarged detail taken on line 6-6 of Fig. 7. Fig. 8 is a diagrammatic view showing a suitable system of electrical connections for the instrument.

Referring to the drawings, 1 designates as a whole a suitable base-plate, across and near one end of which is secured the heel-piece or yoke 3 of a polarized magnet, (designated as a whole 2.) This magnet comprises the usual pair of spools 4, a yoke 5, connecting the pole-pieces 6 of the magnet and provided with upstanding pivot-ears 7, an armature 8, pivoted between said ears, and a biasing bar or permanent magnet 9, which is connected with the heel-piece of the magnet at its lower end and at its upper end overhangs the central portion of the armature 8, all as usual.

Upon the end of the base-plate is arranged a transversely-disposed upstanding supporting plate or standard 10, which is apertured to provide a journal for the rear end of a main shaft 11 of the instrument, arranged to extend therethrough at a point between the two magnet-spoils and about mid-

way of the height of the latter. Upon the end of the main shaft which protrudes through the standard 10 is keyed an escapement-wheel, (designated as a whole 12,) said escapement-wheel having a relatively large hub 13, which is provided at diametrically opposite points with conical wiper-recesses 14 and 14'. These recesses while diametrically disposed are nevertheless longitudinally offset relatively to each other, so that the wiper which coöperates with one recess will not engage the other.

Upon the standard 10 is secured a horizontally-disposed supporting-block 15, and upon opposite sides of this block and respectively insulated therefrom and from each other are secured two sets of spring-contacts, as 16, 17, 18, and 19 and 20, respectively. The spring-contacts 16 and 19 constitute switch-springs and carry at their free ends wipers, as 22 and 23, the latter being insulated from its spring, as indicated at 25. In the normal or zero position of the instrument the two wipers rest within the recesses of the escapement-wheel hub, and the switch-springs 16 and 19, respectively, engage the inner contact-springs 18 and 21. Whenever the escapement-wheel is turned away from the zero position, the wipers ride out of the recesses and upon the periphery of the hub, thereby shifting the contacts between the switch-springs and inner springs to the outer springs. These movements of the switch-springs serve to reverse the polarity of the circuit connections to line, as will hereinafter appear. Stop-studs 26 and 27, interposed between the supporting-block 15 and the respective sets of contact-springs, serve to keep the latter properly spaced, as shown clearly in detail, Fig. 6.

With the teeth of the escapement-wheel is arranged to coöperate a pallet 28, rigidly mounted upon the armature 8 of the magnet and carrying escapement-studs 29 and 30, which alternately engage the teeth of the escapement-wheel in a familiar manner. At one point 12' several teeth are omitted from the periphery of the escapement-wheel, these teeth being omitted at an angular position 50 which registers with the escapement-stud 30 when the wheel is in zero position. The object is to release the escapement-wheel on the last counted-out impulse and let it turn amply sufficient to permit the wiper to fully enter the recesses of its hub, and thus certainly reverse the circuit. A stop-stud 31 is provided upon the inner face of the escapement-wheel, which, as the wheel reaches the zero position, engages an insulated stop 32, mounted upon the standard.

The escapement-wheel is spring-returned to its zero position, the mechanically-operated escapement controlling such return. To effect its return, the main shaft is provided with a fixed collar 33 and loose collar

34, with each of which are connected the respective ends of a coiled spring 35. The collar 34 is held against rotation with the shaft by means of an arm 36, connected therewith (see Fig. 5) and extending downwardly and normally engaging a stud 37 on the base-plate, this arm forming a convenient hanger, whereby the spring may be wound up or permitted to unwind to adjust the tension of the spring.

The manipulation of the escapement-wheel is accomplished through the medium of a setting-dial 38, rigidly mounted upon the forward end of the main shaft, and a setting-arm 39, provided with a thumb-nut 40, which is loosely journaled on the shaft adjacent to the setting-arm and adapted to co-operate with the latter. The setting-arm is provided with a stud 41, adapted to be inserted in any one of a series of apertures 42, 85 formed through the dial in positions corresponding to the several digits, each aperture of course corresponding to one tooth of the escapement-wheel. Normally the setting-arm is held retracted out of range of the dial 90 by means of a coiled expansion-spring 43, interposed between the arm and dial; but when the spring is compressed the stud of the arm can be passed through any given one of the apertures 42 and protruded beyond the 95 rear face of the dial far enough to engage a stop-stud 44, mounted upon a suitable support, usually upon the face of the switchboard. In the preferred construction the stud 44 is carried by an arm 45, one end of which is journaled upon the main shaft of the instrument and the opposite end of which is slotted and secured by a screw 46 to the switchboard, this construction enabling the stud 44 to be adjusted circumferentially of 100 the dial.

As will hereafter appear, the instrument being described is intended for use in conjunction with a suitable mechanism for constantly sending out pulsating current, and inasmuch as reliability of selection depends upon avoiding the sending to line of any fragmentary parts of impulses one of the most important features of the present invention resides in the provision of means 115 whereby incomplete impulses are kept from going to the external circuit and full impulses only sent to line. In the preferred embodiment illustrated this is accomplished by the provision of means which insures that 120 an initial impulse, or it may be part of an impulse, is first sent through the instrument and imparts an initial movement to the latter, and this initial movement of the instrument results in closing the external circuit, 125 so that thereafter full impulses are counted out. Obviously such initial impulse or fragment of impulse is not considered as part of the count. Describing the mechanism for this purpose, and referring more particularly 130

to Figs. 1 and 4, 47 designates a split sleeve, (consisting, as shown, of two half-sleeves 47' and 47''), which are mounted upon the main shaft at a point intermediate the length of the latter and engage the latter frictionally. In order to hold these half-sleeves in light frictional engagement with the shaft, a suitable clamping device is arranged to encircle the sleeve members, consisting, as shown, of a light spiral spring 48, wrapped around the sleeve-sections and having its end secured to stud 49 upon one of the sections. One of these sections 47' carries a rotary projecting contact-arm 50. A bearing-standard 51 is arranged to support the main shaft 11 at a point adjacent to the sleeve-sections, and upon the journal portion of this bearing-standard is adjustably secured a collar 52, provided with a set-screw 53, whereby it is held rigid with the bearing. The collar 52 carries an arm 54, from which extends a stop-finger 55, which projects into the path of the contact-arm 50, the arrangement being such that when the main shaft is turned manually the sleeve-sections and contact-arm carried thereby move with the shaft a slight distance until the contact-arm engages the stop-finger 55, and thus arrests it. This circumferential movement of the contact-arm is less angularly than the distance between the ratchet-teeth of the ratchet-wheel 12. Adjacent to the sleeve-sections and in register with the contact-arm 50 is arranged a second standard 56, insulated from the base-plate, as indicated at 57, and carrying a spring contact-strip 58, which tends to spring outwardly toward the contact-arm 50 and is limited in its outward movement by an adjusting-screw 59. The stop-finger 55 is so adjusted that it will arrest the contact-arm just after the latter has been moved out of electrical contact with the strip 58, but nevertheless far enough away from the latter so that when the ratchet-wheel engages the escapement under the return pressure of its spring the arm 50 and strip 58 will rest out of contact. Obviously the first return step of the main shaft will carry the arm 50 into engagement with the strip 58, and this closes the external circuit, as will hereinafter appear. It may be here noted that the actuation of the escapement is accomplished by a local circuit of a polarity opposite that of the external circuit, and the impulses of which are alternated with those which are sent to the external circuit, from which it follows that no portion of an impulse will be sent to line by the closing of the circuit between arm 50 and contact-strip 58 before the impulse which effects such closing dies away.

The construction of the mechanical features of the instrument having now been described, a simple circuit suitable for the instrument will be readily understood.

Referring to diagrammatic Fig. 8, A design-

nates as a whole diagrammatically the instrument just described, B a suitable source of pulsating current, which may be a pole-changer, and C and D cord-keys with their connected pairs of cords and circuit connections. E and F represent diagrammatically switchboard spring-jacks. The keys C and D, it will be understood, are each susceptible of being shifted in two directions to close the circuit as to the respective ends of the pairs of cords, as usual. The parts shown diagrammatically, which correspond to the parts of the instrument just described, are designated by the same numerals.

Assuming that the plug c or d has been inserted in one of the spring-jacks and selective impulses are to be sent to line, the operator first sets the dial at the proper numeral by rotating the arm 39, (not shown in the diagram,) inserting it in the aperture 42 of the desired numeral, and thereafter rotating dial and arm together until arrested by the engagement of the pin 41 with the stop-stud 44. In the initial movement of the dial the circuit between contact-arm 50 and contact-strip 58 is open. The cord-key being now shifted in the proper direction, the pulsating current which actuates the escapement may be traced as follows, it being noted that the rotary movement of the hub 13 of the ratchet-wheel shifts switch-springs 16 and 19 into contact with back springs 17 and 20, respectively, and opens the contact between switch-springs 16 and forward spring 18.

Starting at brush b of the generator, the circuit extends to springs 19 20, thence to and through the coils of the actuating-magnet 2, thence to a bus-line 59, with which each of the cords is connected by means of conductors 60. Springs 61, 62, and 63 being at this time in contact, the circuit is from conductor 60 over line 64 to springs 63 and 62 and from thence back to the return bus-line 59' over conductors 65 and 66. From bus-line 59' a conductor 67 leads back to the constantly-closed pole of the generator. This circuit energizes the magnet 2 in the proper direction to retract the escapement-tooth 29, whereupon the ratchet-wheel returns one step, thus closing the circuit between contacts 50 and 58. The pole-changer in its further rotation or movement now closes circuit through its brush or contact device b', which has theretofore been in engagement with the insulated part b'' of the pole-changer, thus closing the external circuit, which may be traced as follows: from brush b' to springs 17 and 16, thence to contacts 50 and 58, and thence to a bus-line 68, connected with each of the cord circuits by conductors 69. Springs 70 and 71 of the cord-key are at this time closed, spring 70 being connected by a conductor 72 with conductor 69 and spring 71 with the tip side of the plug. From the tip of the plug the

circuit extends out over one side of the telephone-line, back over the other to the sleeve side, and thence through springs 61 and 62, conductors 65 and 66 to the common return bus-line 59', and thence to the pole-changer, as before.

The two circuits described will be alternately closed by the continued rotation or movement of the pole-changer until the 10 ratchet-wheel reaches its zero position, whereupon the wipers of the two switch-springs 16 and 19, entering the recesses of the hub 13, will simultaneously cross the connections of the external circuit and open the local circuit 15 so as to prevent further pulsations from going through the magnet.

The use and operation of the mechanism has been fully set forth in connection with the foregoing description and need not, 20 therefore, be repeated. It is to be observed, however, that the instrument is perfectly adapted for use in conjunction with any constantly-running source of pulsating current, such as a dynamo or pole-changer and battery, or it may be connected in with an ordinary hand-operated magneto having its connections arranged to correspond to those of the generator shown diagrammatically in Fig. 8. It will be noted that with the 25 circuits connected as described the full strength of the current is sent over the external line, thus enabling the selective apparatus to be operated with great certainty and reliability. It is further to be noted that the external 30 circuit is not opened by the counting instrument between impulses after it has been initially closed, so that imperfect selections due to failure of make-and-break contacts are practically avoided. The fact that 35 the escapement is operated by those impulses which occur in alternation to the impulses sent to line permits an extremely speedy operation of the instrument, because the shifting from tooth to tooth of the ratchet-wheel occurs between those periods during 40 which current is being sent over the external circuit. The movement of the counter-wheel is of course immaterial after the circuit has been initially closed and until 45 it is reversed at the end of the count; but it is highly important that the reversal which occurs at the time the counter reaches its zero position should be fully performed between impulses, since otherwise a false impulse 50 might be sent to line. In this connection it may be noted that the interruption of the teeth of the ratchet-wheel at the angular point which corresponds with the zero position of the wheel insures that the wheel shall 55 step forward during its last step to zero amply far enough to bring the wipers 22 and 60 23 into full engagement with the recesses of the ratchet-wheel hub, and thus insures a certain reversal of the circuit. As ordinarily

employed, this instrument is so connected 65 as to count out a series of impulses of one polarity and then to ring a polarized bell by the succeeding impulses of opposite polarity at the instrument selected, although of course it is not essential that the instrument be employed for controlling the ringing-current, and if it be not so employed the switch-springs may be made to simply open the external circuit instead of reversing it.

I claim as my invention—

1. An electrical-impulse-counting device, comprising a ratchet member, an electrically-actuated escapement mechanism controlling the movement of said ratchet member, means for sending electrical pulsations through said 80 counting device, and means actuated by the controlling device for closing a working circuit after the initial actuation of the instrument whereby the sending of fragmentary impulses over said working circuit is avoided. 85

2. An automatic impulse-counter, comprising a ratchet member having teeth corresponding to a progressively-regular series of numerals means for setting said ratchet-wheel initially in position corresponding to 90 any desired one of said numerals, electromagnet mechanism for controlling said ratchet member, circuit connections for said electromagnet mechanism, a working circuit, contact devices controlling said working circuit 95 and actuated by said electromagnet mechanism, and means for sending current pulsations over each of said circuits.

3. An automatic impulse-counter, comprising an automatically-returned ratchet 100 member, electromagnet mechanism for controlling said ratchet member, circuit connections for said electromagnet mechanism, a working circuit, contact devices controlling said working circuit and actuated by said 105 electromagnet mechanism, means for manually setting said ratchet member at any predetermined number of steps from zero, and means for sending current pulsations over each of said circuits. 110

4. An automatic impulse-counter, comprising a spring-returned ratchet-wheel, an escapement controlling said ratchet-wheel, a magnet for actuating said escapement, circuit connections for said magnet, a working 115 circuit, and means for sending pulsations of opposite polarity alternately through said magnet and over said working circuit.

5. An automatic impulse-counter, comprising a spring-returned ratchet-wheel, an 120 escapement controlling said ratchet-wheel, a magnet for actuating said escapement, circuit connections for said magnet, a working circuit, contact devices controlling said working circuit and controlled by said magnet, 125 and means for sending current impulses alternately through said magnet and over said working circuit, those pulsations which were

sent through the magnet being of opposite polarity from those which were sent over the working circuit.

6. In combination with an independently-running source of recurrent electrical pulsations, a counting mechanism controlled by and operating in synchronism with said pulsations, and itself controlling pulsations sent to a line-circuit, and means operating automatically to arrest the sending of impulses of like character to line at the end of a preset count.

7. In combination with an independently-running source of recurrent electrical pulsations, a counting mechanism controlled by and operating in synchronism with said pulsations, and itself controlling pulsations sent over a line-circuit, means operating automatically to arrest the sending of impulses of like character to line at the end of a preset count, and means operating automatically to place the line-circuit initially in effective condition during an interval between these pulsations which are sent to line, whereby fragmentary portions of full pulsations are prevented from being sent over the line-circuit.

8. In combination with an independently-running source of alternating electrical pulsations, a counting mechanism controlled by and operating in synchronism with the pulsations of one polarity, means controlled by said counting mechanism and operating to send over a line-circuit pulsations of opposite polarity, and means operating automatically to arrest the sending of impulses of like character to line at the end of a preset count.

9. In combination with an independently-running source of recurrent electrical pulsations, a counting mechanism controlled by and operating in synchronism with said pulsations, means controlled by said counting mechanism for sending pulsations to a line-circuit, and means operating automatically to reverse the pole connections of said line-circuit at the end of a preset count.

10. In combination with a source of current generation, pole-changing mechanism, connected circuits comprising positive and negative contact devices and a conductor connected with each, a common-return conductor constantly connected with the source of generation and also connected with said positive and negative conductors, a counting mechanism controlled by and operating in synchronism with the pulsations sent over one of said circuits, and means controlled by said counting mechanism operating automatically to arrest the sending of impulses of opposite polarity over the other circuit at the end of a preset count.

11. In combination with a source of current generation, pole-changing mechanism, connected circuits comprising positive and negative contact devices and a conductor connected with each, a common-return con-

ductor constantly connected with the source of generation and also connected with said positive and negative conductors, a counting mechanism controlled by and operating in synchronism with the pulsations sent over one of said circuits, and means controlled by said counting mechanism operating automatically to arrest the sending of impulses of opposite polarity over the other circuit at the end of a preset count and to effect the sending of a series of impulses of opposite polarity over said latter circuit.

12. In combination with an independently-running source of recurrent electrical pulsations, a counting mechanism controlled by and operating in synchronism with said pulsations, means for manually setting the counter member of said counting mechanism and means for closing a circuit subsequent to the initial movement of said counter member comprising a contact device mounted to move with said counter and frictionally driven by the latter, a coöperating contact device, and a stop arranged to limit the movement of the frictionally-driven contact device away from its coöperating contact.

13. In combination with an independently-running source of recurrent electrical pulsations, a counting mechanism comprising a ratchet-wheel, means for setting said ratchet-wheel manually, electrically-actuated means for effecting a step-by-step movement of the ratchet-wheel, and means for closing a circuit by, and subsequent to, the initial counting movement of the ratchet-wheel comprising a contact device frictionally mounted upon a part rotating with the ratchet-wheel, a relatively stationary coöperating contact device, and a stop for limiting the arc of movement of the frictionally-driven contact device.

14. A counting mechanism comprising a main shaft, a ratchet-wheel mounted thereon, a spring tending to normally return said ratchet-wheel to a definite position, an electrically-actuated escapement mechanism controlling the return of the ratchet under the action of said spring, and means for manually advancing the ratchet-wheel in a predetermined number of steps.

15. A counting mechanism comprising a main shaft, a ratchet-wheel mounted thereon, a spring tending to normally return said ratchet-wheel to a definite position, an electrically-actuated escapement mechanism controlling the return of the ratchet under the action of said spring, and means for manually advancing the ratchet-wheel in a predetermined number of steps comprising a dial rigid upon the main shaft, an arm adapted to be engaged with said dial at points corresponding to the angular positions of the several ratchet-teeth, and a stop arranged to arrest the movement of the interengaged arm and dial at a definite angular position.

16. An electrical impulse-counting mech-

- anism comprising a spring-actuated main shaft, a ratchet-wheel mounted thereon, an escapement mounted to coöperate with said ratchet-wheel, a magnet arranged to operate said escapement, a dial mounted upon said main shaft and provided with recesses or apertures corresponding to the several angular positions of the ratchet-teeth, a setting-arm loosely journaled concentric with the dial and provided with a finger adapted to engage the recesses or apertures of the dial, and a stop mounted in position to engage and arrest the oscillatory movement of the arm when the latter is interengaged with the dial.
17. An electrical impulse-counting mechanism comprising a spring-actuated main shaft, a ratchet-wheel mounted thereon, an escapement mounted to coöperate with said ratchet-wheel, a magnet arranged to operate said escapement, a dial mounted upon said main shaft and provided with recesses or apertures corresponding to the several angular positions of the ratchet-teeth, a setting-arm loosely journaled concentric with the dial and provided with a finger adapted to engage the recesses or apertures of the dial, a spring arranged to normally hold the arm retracted from the dial, and a stop mounted in position to engage and arrest the oscillatory movement of the arm when the latter is interengaged with the dial.
18. An electrical impulse-counting mechanism comprising a main shaft, a ratchet-wheel mounted thereon, an escapement controlling the ratchet-wheel, a magnet arranged to operate said escapement mechanism, a cam rotating with the ratchet-wheel, a wiper arranged to coöperate with said cam and contact devices controlled by said wiper.
19. An electrical impulse-counting mechanism comprising a main shaft, a ratchet-wheel mounted thereon, an escapement mechanism controlling the ratchet-wheel, a magnet arranged to operate said escapement mechanism, a circular cam mounted to rotate with said ratchet-wheel and provided with a peripheral recess, a switch-spring wiper co-operating with said cam, and front and back contacts with which said switch-spring coöperates.
20. An electrical impulse-counting mechanism comprising a main shaft, a ratchet-wheel mounted thereon, an escapement mechanism controlling the ratchet-wheel, a magnet arranged to operate said escapement mechanism, a circular cam mounted concentrically with said ratchet-wheel and moving with the latter, said cam being provided with diametrically opposite recesses, a pair of switch-springs, each carrying a wiper, arranged to coöperate with said cam, and back and front contact devices coöperating with said switch-springs.
